DISPENSER CAP FOR A PRESSURIZED CONTAINER

Robert P. Vuillemenot, Oradell, N.J., and Thomas B. Aldrich, New York, N.Y., assignors to The Procter & Gamble Company, Cincinnati, Ohio

Filed Nov. 21, 1966, Ser. No. 4,746

Term of patent 14 years

(Cl. D58—26)

Fig. 1

Fig. 2

Fig. 3

FIG. 1 is a rear elevational view of a dispenser cap for a pressurized container, showing our new design.

FIG. 2 is a front elevational view of the same; and

FIG. 3 is a top plan view of the same.

We claim:

The ornamental design for a dispenser cap for a pressurized container, as shown.
